UNITED STATES PATENT OFFICE.

GEORGE E. HOMER, OF BOSTON, MASSACHUSETTS.

DESIGN FOR A FOB-CHAIN OR SIMILAR ARTICLE.

SPECIFICATION forming part of Design No. 36,623, dated November 17, 1903.

Application filed September 3, 1903. Serial No. 171,834. Term of patent 7 years.

To all whom it may concern:

Be it known that I, GEORGE E. HOMER, a citizen of the United States, residing at Boston, in the county of Suffolk, State of Massachusetts, have invented a certain new, original, and ornamental Design for Fob-Chains or Similar Articles, as shown in the accompanying drawings.

Figures 1 and 2 of the said drawings show, respectively, the opposite sides of a fob-chain embodying my design.

I claim—

The ornamental design for a fob-chain, or similar article, as shown.

In testimony whereof I affix my signature 15 in presence of two witnesses.

GEO. E. HOMER.
